[57] CLAIM

The ornamental design for an accessory connector, as shown and described.

DESCRIPTION

FIG. 1 is a bottom plan view of an accessory connector in accordance with the present invention;

FIG. 2 is a top plan view of the accessory connector of FIG. 1;

FIG. 3 is a first side elevational view of the accessory connector of FIG. 1 showing a fixed latch;

FIG. 4 is a second side elevational view of the accessory connector of FIG. 1 showing a pivotable latch;

FIG. 5 is an isometric view of the accessory connector of FIG. 1 showing the pivotable latch; and,

FIG. 6 is an isometric view of the accessory connector of FIG. 1 showing the fixed latch.

The broken line showing throughout the drawing figures is included for the purpose of illustrating environmental structure only and forms no part of the claimed design.

FIG. 1

FIG. 3

FIG. 2

FIG. 4
